UNITED STATES PATENT OFFICE.

LUTHER C. THOMPSON, OF WASHINGTON, DISTRICT OF COLUMBIA, ASSIGNOR TO
FERDINAND FRANZ, OF BALTIMORE, MARYLAND.

THRUST-BEARING JOURNAL-BOX.

1,141,667.

Specification of Letters Patent.

Patented June 1, 1915.

Application filed September 29, 1913. Serial No. 792,477.

To all whom it may concern:

Be it known that I, LUTHER C. THOMPSON, a citizen of the United States, and a resident of the city of Washington, District of Columbia, formerly of Baltimore, Maryland, have invented a new and Improved Thrust-Bearing Journal-Box, of which the following is a full, clear, and exact description, that will enable those skilled in the art to make and use the same, reference being had to the accompanying drawings, that form a part of this specification.

This my invention relates to thrust-bearing journal boxes for the equipment of traction cars or motor cars, including any and all kinds of trucks that are propelled by steam or electric power.

My object is to provide an improved thrust-bearing journal box and by this means to cushion the centrifugal force of the car when passing around curves, and thereby check vibration when and where it originates. This journal-box is journaled on the axle, and compression springs are interposed in said box and are also substantially connected in union, supporting the box on the axle, permitting the box to reciprocate on the axle in a manner to compress the said cushion springs and thereby check any side thrust of the car.

Another object in view is to provide yielding supports for the axle journal in said box and to thereby reduce the shearing cut of the wheel flanges on the rails when passing around the curves of the road, thereby overcoming the compound wheel friction of resistance and economizing in motive power at the curves of the road. The reciprocating movements of the journal-boxes on the axles compress the springs, offering a yielding cushion support, during the side thrust of the car and its load, and

by this means, the force of the blows at the side of the rails and on the wheel-flanges, are checked, thus, affording means of governing car oscillation and permitting of higher speed with greater safety.

Figure 1 is a longitudinal side elevation. Fig. 2 is a vertical cross section. Fig. 3 is a longitudinal cross section. Fig. 4 is an end elevation of the rear of box. Fig. 5 is a face view of the cross bar.

The springs 8. 8 are inserted in the channels A. A. of box 10, and the draw-bars F. F. are also inserted in the compression springs 55 8. 8. and they pass through the lugs G. G. and are rigidly connected with cross-bars 15 at 10 $\frac{1}{2}$ —10 $\frac{1}{2}$.

The heads T. T. rest on one end of springs 8. 8. that are interposed between 60 said heads T. T. and lugs G. G., axle journal D having a central support on the cross-bar 15.

All parts are connected in box 10 in a manner to check the momentum of any side 65 thrust of the car and its load, as herein set forth.

Having thus described my invention, what I claim as new in thrust-bearing journal boxes, and desire to secure by Letters Patent, is:—

In a thrust-bearing, the combination of a journal-box having lugs near one end thereof, an axle, a bar extending across the end of the axle, drawbars attached to the cross-bar at one end, and having heads at the opposite ends, the draw-bars passing through said lugs, and compression springs surrounding the draw-bars between said heads and said lugs, all for the purpose set forth. 80

LUTHER C. THOMPSON.
